UNITED STATES PATENT OFFICE.

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE.

SHEET-FOLDING MECHANISM.

Application filed April 2, 1927. Serial No. 180,501.

In sheet folding mechanism where coacting floating folding jaws and blades are used to impart the fold to the sheet or group of sheets it has been found that the stationary 5 cam which controls the opening and closing of the folding jaws was somewhat inaccurate in the time of closing the jaws, due to the fact that when the roller of the jaw opening and closing lever engaged the cam 10 to open the jaws, it would be caused to jump away from the cam and the exact point of its return to the cam surface on the jaw closing incline thereof was somewhat uncertain as well as causing a considerable 15 amount of noise and also undue wear on both the roller and the cam, thereby making their coaction even more inaccurate.

The object of my invention is to provide an extensible and contractible cam for controlling the opening and closing of the floating folding jaws, the cam part which controls the opening of the jaws being fixed and the cam part which controls the closing of the jaws being adjustable longitudinally, 25 concentric with the axis of the folding jaw carrier.

A practical embodiment of my invention is represented in the accompanying drawings, in which

30 Fig. 1 represents a detail front view of the folding jaw carrier and its adjacent parts at one end thereof.

Fig. 2 represents a cross section taken in the plane of the line II—II of Fig. 1, looking in the direction of the arrows.

Fig. 3 represents a detail cross section taken in the plane of the line III—III of Fig. 1, looking in the direction of the arrows.

40 Fig. 4 represents a detail section taken in the planes of the line IV—IV of Fig. 3, looking in the direction of the arrows.

Fig. 5 represents a detail view taken in the plane of the line V—V of Fig. 3, looking in the direction of the arrows.

The floating folding jaws of each pair are denoted by 1, 2, which jaws are mounted to oscillate in the usual manner in suitable bearing supports 3 fixed to the rotary carrier 4. The jaw floating control lever 5 is provided with the usual roller 6 arranged to travel in the endless groove 7 of the sta-

tionary box cam 8 for oscillating the jaws to float them into and out of their folding position.

To counteract the centrifugal force of the jaws as they are floated into and out of their folding position so that the roller 6 will be held against the inner wall of the cam groove 7, I provide a bell crank lever pivoted at 9 on the rotary carrier 4 adjacent to its pair of folding jaws 1, 2. A pressure spring 10 exerts its tension against one arm 11 of the bell crank lever, the other arm 12 of said lever having its outer end positioned to engage an abutment 13 on the folding jaw 1 as the jaws are being floated into and out of their folding position. The tension of this spring 10 may be regulated to exert the required pressure on the abutment 13 of the folding jaw 1 to hold the roller 5 against the inner wall of its cam groove 7 as the folding jaws are moved into and out of their folding position.

The opening and closing of the folding jaws as they are moved to and from their folding position is controlled by the lever 14 projecting from the rock shaft 15 to which the folding jaw 2 is secured, said lever being provided with a roller 16 arranged in position to be engaged by the extensible and contractible cam, the fixed and adjustable parts of which are denoted by 17, 18. A spring 19 exerts its tension on the lever 14 for yieldingly holding the lever at the limit of 80 its inward movement and thereby the jaw 2 closed against the jaw 1.

The fixed part 17 of the cam 17, 18 is secured in its proper position on the box cam 8, in the present instance by the bolts and nuts 20, 21. This part of the cam first engages the roller 16 on the lever 14 for controlling the opening of the jaws as they come to their folding position.

The other part 18 of the cam is adjustably 95 secured to the box cam 8 by the bolts and nuts 22, 23, the bolts 22 passing through elongated slots 24. This adjustment of the cam part 18 is along a line concentric with the axis of the rotary carrier 4. By this arrangement the concentric surface of the cam may be extended and contracted and the position of the inclined surface of the cam which controls the closing of the jaws may

be properly positioned to control the closing of the jaws at the exact time onto the folded product.

It will also be seen that counterbalancing means for counteracting the centrifugal action of the jaws not only tends to hold the roller 6 of the jaw floating control lever at the limit of its inward movement but also tends to prevent the jumping of the roller 16 10 of the jaw opening and closing lever away from the surface of its extensible and contractible cam 17, 18, thereby materially lessening the noise and preventing undue wear of the parts as well as ensuring accuracy in 15 the closing of the jaws.

It is evident that various changes may be resorted to in the construction, form and arrangement of the several parts without departing from the spirit and scope of my invention; hence, I do not wish to be limited 20 to the particular embodiment herein shown and described, but

What I claim is:—

1. In a folding mechanism, a rotary carrier, a pair of folding jaws carried thereby, and means for controlling the opening and closing of the jaws, said means including an extensible and contractible cam.

2. In a folding mechanism, a rotary carrier, a pair of floating folding jaws carried thereby, means for floating said jaws to and from their folding position, and means for controlling the opening and closing of the jaws, said means including an extensible and 35 contractible cam.

3. In a folding mechanism, a rotary carrier, a pair of folding jaws carried thereby, and means for controlling the opening and closing of the jaws, said means including an

extensible and contractible cam having a 40 fixed part for controlling the opening of the jaws and an adjustable part for controlling the time of closing of said jaws.

4. In a folding mechanism, a rotary carrier, a pair of floating folding jaws carried thereby, means for floating said jaws to and from their folding position, and means for controlling the opening and closing of the jaws, said means including an extensible and contractible cam having a fixed part for controlling the opening of the jaws and an adjustable part for controlling the time of closing of said jaws.

5. In a folding mechanism, a rotary carrier, a pair of folding jaws carried thereby, and means for controlling the opening and closing of the jaws, said means including an extensible and contractible cam having a fixed part for controlling the opening of the jaws and another part adjustable along a 50 line concentric with the axis of the carrier for controlling the time of closing of said jaws.

6. In a folding mechanism, a rotary carrier, a pair of floating folding jaws carried thereby, means for floating said jaws to and from their folding position, and means for controlling the opening and closing of the jaws, said means including an extensible and contractible cam having a fixed part for controlling the opening of the jaws and another part adjustable along a line concentric with the axis of the carrier for controlling the 70 time of closing of said jaws.

In testimony, that I claim the foregoing as my invention, I have signed my name this 75 30th day of March 1927.

HOWARD M. BARBER.
